UNITED STATES PATENT OFFICE.

WALTER O. LEE, OF DETROIT, MICHIGAN.

BUTTON.

1,336,243.

Specification of Letters Patent.

Patented Apr. 6, 1920.

Application filed October 31, 1919. Serial No. 334,636.

To all whom it may concern:

Be it known that I, WALTER O. LEE, a citizen of the United States, residing at Detroit, in the county of Wayne and State of Michigan, have invented certain new and useful Improvements in Buttons, of which the following is a specification.

This invention relates to a tie button and has for its object a tie button which can be used to hold the two ends of a four-inch hand tie together or hold any tie to the shirt. It has for its object a button of simple construction but reliable operation. The base of the button is of special construction to hold the head and stem in as rigid relation with the base as is possible. These and other objects will appear when the detail construction is understood.

In the drawings,—

20 Figure 1 is a longitudinal section of the button.

Fig. 2 is an elevation of the spring-retaining sleeve.

25 Fig. 3 is a plan view of the spring-retaining sleeve.

The head is designated *a*, the base *b*, and the stem *c*. The head is formed with a pair of disks *d* and *e*. *f* designates the lining for the head, which may be sheet metal.

30 The stone *g* is set above the disk *e* and is cut with a slightly projecting ring *h*. A double packing ring *i* is adapted to engage on the outside of this ring portion of the stone, while an annular member *j* is adapted to be 35 crimped under the lining *f*, over the peripheries of the disks and over the rings *i* and the ring portion *h* of the stone, thereby assembling all the parts of the head together.

40 The stem *c* has a sharp point *k* calculated to make it possible to pierce any fabric very readily. Somewhat above the place where the taper for the point begins is an annular groove *l*.

45 The base is formed with three parts that easily fit together. The circular plate *m* has a cylindrical neck drawn from its center as at *n*. The neck has a turned-in lip *o* adapted to engage closely against the stem 50 to prevent the stem from moving laterally with respect to the base. Within this

drawn neck portion *n* is a specially constructed spring sleeve *p* which is almost the same shape as the neck portion, being a cylinder split part way down with in-turned 55 prongs *q* which are adapted to engage in the annular groove *l* of the stem. The cylindrical interior of this sleeve is only slightly larger than the cylindrical portion of the stem *c* between the annular groove *l* 60 and the beginning of the taper that forms the point *k*. Hence this intervening portion engaging with the walls of the spring sleeve and the stem engaging closely with the lip *o* of the neck serve as a two-point 65 bearing, the contacts being at somewhat spaced points to hold the stem as nearly erect with respect to the base as possible. This is quite a marked improvement over the previous buttons of this character. The 70 opposite end of the sleeve *p* is flared out into a bell as at *r*, this engaging under the circular plate at the point where it merges into the neck *n*. The lining disk *s* has its edges turned over the periphery of the circular 75 plate *m* and this serves to tightly hold the flared end of the spring sleeve *p* in engagement with the circular plate and also covers the opening into the neck portion.

The prong *t* is soldered on to the lining *f* 80 and serves to embed itself in a fabric to prevent the turning of the head.

What I claim is:

A neck-tie button, having in combination, 85 a head, a stem with a pointed end attached thereto and having an annular groove near its pointed end but with an intervening cylindrical portion, a base having a drawn-in perforated center through which the stem passes and adapted to engage around the 90 portion of the stem between the annular groove and the head, and a sleeve secured to the base within the drawn-in center and fitting closely around the cylindrical portion of the stem intervening between the 95 groove and pointed end, the end of the sleeve facing the head being split and turned in to be of less diameter than the stem to form spring prongs which can engage in the annular groove of the stem. 100

In testimony whereof I affix my signature.

WALTER O. LEE.
